UNITED STATES PATENT OFFICE.

ERNEST CECIL COX, OF NEWPORT NEWS, VIRGINIA.

SIGNALING DEVICE FOR AUTOMOBILES.

1,222,078.

Specification of Letters Patent. Patented Apr. 10, 1917.

Application filed April 19, 1916. Serial No. 92,223.

To all whom it may concern:

Be it known that I, ERNEST C. Cox, a citizen of the United States, and a resident of Newport News, in the county of Warwick and State of Virginia, have invented a certain new and useful Improvement in Signaling Devices for Automobiles, of which the following is a specification.

My invention relates to improvements in signaling devices for automobiles, and it consists in the combinations, constructions, and arrangements herein described and claimed.

An object of my invention is to provide a signal which may be located at the rear of the vehicle, as for instance, on the fender, said signal being normally out of view but being arranged to be brought into view immediately by the pressure of a push button.

20 A further object of my invention is to provide a device of the type described in which the operating parts are few, and are therefore not liable to easily get out of order.

Other objects and advantages will appear 25 in the following specification, and the novel features of the invention will be particularly pointed out in the appended claims.

My invention is illustrated in the accompanying drawings forming part of this 30 application, in which:

Figure 1 is a view showing my invention applied to a vehicle.

Fig. 2 is a section along the line 2—2 of Fig. 3.

35 Fig. 3 is a section along the line 3—3 of Fig. 2.

Fig. 4 is a detail sectional view showing the circuit closer for the light.

Fig. 5 is a sectional view along the line 40 5—5 of Fig. 2.

Fig. 6 is a sectional view along the line 6—6 of Fig. 5.

Fig. 7 is a diagrammatical view of the circuit connection.

45 In carrying out my invention I provide a casing 1 in which is disposed a magnet M, in this instance of the double fold type, whose armature A is pivotally connected at one end by means of a link 2 with the bell 50 crank lever 3 which is fulcrumed at 4.

Mounted on the base 5 of the casing is the sleeve 6 which forms a socket for a shaft 7 bearing a signal 8 having the word "Stop" or some similar legend thereon. A spiral 55 spring 9 surrounds the shaft 7, one end of the spiral spring engaging the casing 1, see

Fig. 3, and the other end being secured to the shaft 7.

Extending from the shaft 7 is an arm 10 having a contact finger 11. The arm 10 is connected by means of a link 12 with the end of the bell crank lever 3, and the spring 9 tends to keep the parts normally in the position shown in Fig. 2, in full lines, in which the armature A is held away from the magnet M.

At 13 I have shown a light whose base bears against the spring 14 carried by the housing 15, the end of the spring bearing 70 against the head of a slidible pin 16.

From the foregoing description of the various parts of the device, the operation thereof may be readily understood. The circuit connections are those shown in Fig. 7, in which the battery B is brought into circuit with the magnet M when the push button P is closed. This attracts the armature A which, through the medium of the link 2, lever 3, link 12, arm 10, turns the shaft 7, so as to bring the signal 8 into the position 75 shown in Fig. 1 in which the legend is displayed to the rear of the vehicle. At the same time that the arm 10 is moved, the finger 11 comes into contact with the pin 16, thereby tending to press the pin inwardly 80 against the spring 14. If the switch S, see Fig. 7, should be closed, then current from the battery B' would flow through the lamp 13, thus causing the latter to light up. This lamp may be a red lamp or any other suitable color.

It will be noted that the spring 14 plays a double function. In the first place, it cushions the movement of the signal, and thus prevents jar which might otherwise 95 tend to rattle the parts. It also serves as a means for insuring a good circuit connection, since the pin may be moved inwardly and the contact becomes closer as the pin is pressed on by the finger 11. Immediately 100 on the release of the push button, the magnet M is deenergized and the parts are restored to their normal position by means of the spring 9.

I claim:

1. In an automobile signal, a magnet, an armature therefor, a rock shaft, a stop arm carried thereby, means for energizing the magnet, means connected with said armature for moving said rock shaft, a signal carried 110 by the shaft and arranged to move with it, and means arranged to be engaged by said

- stop arm for cushioning the movement of the rock shaft, said cushioning means comprising a pin arranged to be engaged by said stop arm, a spring arranged to bear against said pin, an electric lamp having its base bearing on the opposite end of the spring, and circuit connections for causing the lamp to be lighted when the stop arm engages the pin.
- 10 2. In a signaling device for automobiles, a magnet, means for energizing the magnet at will, an armature for said magnet, a rock shaft, a signal device carried by the rock shaft, lever and link connections between said armature and said rock shaft for rocking the latter, a stop arm carried by said

rock shaft, a movable pin arranged to be engaged by said stop arm, a spring for cushioning the pin, an electric lamp having connections with the spring at the opposite end from the pin, a spring carried by the rock shaft and arranged to be placed under tension during the movement of the armature for restoring the parts when said armature is released, and circuit connections arranged to be established through the electric lamp on the engagement of the pin by the stop arm. 20 25

ERNEST CECIL COX.
